BOTTLE

Henry A. Markus, Chicago, Ill.

Application December 10, 1956, Serial No. 44,133

Term of patent 14 years

(Cl. D58—6)

Fig. 1 is an elevational view of the front of a bottle, showing my new design;

Fig. 2 is a corner elevational view thereof; and

Fig. 3 is a top plan view thereof.

The sides of the bottle not shown are the same as the sides shown.

The dominant features of the design are shown in solid lines.

I claim:

The ornamental design for a bottle, substantially as shown and described.
